Primary Examiner — Robert M Spear*Assistant Examiner* — Kendra L Hamilton(74) *Attorney, Agent, or Firm* — Waller Lansden Dortch & Davis LLP; Matthew C. Cox(57) **CLAIM**

What is claimed is the ornamental design for an animal crate door, as shown and described.

DESCRIPTION

FIG. 1 is a front-right perspective view of an animal crate door, showing my new design;

FIG. 2 is a rear-left perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is a front-right perspective view, shown in an environment of use;

FIG. 10 is a front elevational view thereof;

FIG. 11 is an alternate front-right perspective view, shown in an environment of use; and,

FIG. 12 is a front elevational view thereof.

In FIGS. 1-8, the broken lines illustrate portions of the animal crate door that form no part of the claimed design. In

(Continued)

FIGS. 9, 10, 11 and 12, the broken line showing of a dog crate depicts unclaimed environmental subject matter.

1 Claim, 10 Drawing Sheets
